UNITED STATES PATENT OFFICE.

JOHN A. SHEA, OF WILKES-BARRE, PENNSYLVANIA.

GARMENT-HANGER.

1,072,179.

Specification of Letters Patent.

Patented Sept. 2, 1913.

Application filed July 10, 1912. Serial No. 708,716.

To all whom it may concern:

Be it known that I, JOHN A. SHEA, citizen of the United States, residing at Wilkes-Barre, in the county of Luzerne and State of Pennsylvania, have invented certain new and useful Improvements in Garment-Hangers, of which the following is a specification.

This invention relates to garment hangers and more particularly to an improvement in hangers such as are arranged within garment display cases employed in clothing stores for the purpose of displaying coats, skirts, jackets, and other articles of wearing apparel. Such hangers ordinarily include as an essential feature a bar which is slidably supported beneath the top of the display case and with which are to be engaged the hooks of ordinary coat or skirt hangers. In exhibiting garments to a customer, it is at present customary for the clerk to remove one or more of the garments and the hangers therefor from this rod or bar and lay the garment upon a table or counter, and where a number of garments must be shown, or where a number of clerks are removing garments at the same time from a single display case, it almost invariably happens that the garments are piled promiscuously upon one another regardless of the size, style, or other distinctive characteristics. It also not infrequently happens that a customer after looking at a number of garments will decide upon purchasing the first or second one shown and it is then necessary for the salesman to search through the entire pile of garments upon the table or counter in order to locate the one desired. Not only does this result in the garments becoming mussed and rumpled, but with certain styles of hangers they are liable to be torn, unless carefully pulled from the pile. Furthermore, considerable time is lost and trouble occasioned by this method of displaying the garments. Aside from the disadvantages mentioned above, a customer cannot, with any degree of satisfaction examine a garment which is spread out upon a table among numerous other garments in a more or less rumpled state.

The present invention therefore aims to provide a hanger of the class mentioned with an auxiliary hanger rod which may be extended in advance of the main hanger rod and will be adapted to support the garments to be displayed in properly draped position,

and in such manner that they may be conveniently and satisfactorily examined.

For a full understanding of the invention reference is to be had to the following description and accompanying drawing, in which:

Figure 1 is a perspective view of a hanger constructed in accordance with the present invention. Fig. 2 is a plan view of the forward portion of the hanger illustrating the manner in which the auxiliary hanger is mounted and is to be extended when the door of the case in which the device is arranged, is open. Fig. 3 is a detail vertical longitudinal sectional view through the hanger embodying the present invention. Fig. 4 is a vertical transverse sectional view on the line 4—4 of Fig. 3.

Corresponding and like parts are referred to in the following description and indicated in all the views of the accompanying drawing by the same reference characters.

In the drawing, the reference character A indicates in general the top of a display case and B the hinged door thereof. This case and its door may be of any ordinary form. Arranged upon the under side of the top of the casing A is a guide 1 in which is mounted a slide 2, the guide having oppositely arranged channels 3, and the slide 2 having flanges 4 which slidably fit in the said channels. A bracket 5 projects downwardly from the rear end of the slide 2 and a head 6 is arranged at the forward end of the said slide. A hanger rod 7 is secured at its rear end to the bracket 5 and at its other end to the head 6 and with this rod may be engaged the hooks 8 of the ordinary coat and skirt hangers 9 upon which the garments to be displayed may be draped. The head 6 is provided with a downwardly projecting handle 10 which may be grasped for the purpose of sliding the slide and the hanger rod 7 supported thereby, outwardly and inwardly, as may be desired. The construction and arrangement of parts so described does not differ materially from the ordinary types of such devices now in general use, and it will be apparent that it possesses the very disadvantages above mentioned.

The auxiliary hanger device embodying the present invention and which is designed to overcome the disadvantages pointed out above will now be described.

The device consists essentially of a bracket formed of two members, one of which con-

sists of a curved plate 11 provided at one end with a semi-cylindrical sleeve 12 and at its other end with a semi-cylindrical sleeve 13. The other member of the bracket 5 consists of a plate 14 curved to conform to the curvature of the plate 11 and provided at one end with a semi-cylindrical sleeve portion 15 and at its other end with a sleeve portion 16. The convex side of the plate 14 10 is disposed against the concaved side of the plate 11, in assembling the plate and bracket with the sleeves 12 and 15 and the sleeve portions 13 and 16 matching, respectively, and the sections are held in assembled relation by 15 means of bolts 17 which are secured through the plates 11 and 14 and have nuts 18 threaded upon them. The sleeve sections 13 and 16 of the bracket embrace the forward end-portion of the hanger rod 7 and the 20 sleeve portion 16 is formed with spaced lugs 19 which engage with shoulders 20 formed at the junction of the upper end of the handle 10 with the head 6, the bracket being in this manner supported against turning 25 movement upon the said hanger rod 7. By referring to Figs. 1 and 4 of the drawing it will be observed that the plates 11 and 14 extend upwardly and laterally from the sleeve portions 13 and 16 and that as a consequence 30 the sleeve which is formed by the matching sleeve portions 12 and 15 is located above and to one side of the forward end of the hanger rod 7. This last mentioned sleeve is designed to slidably support 35 the auxiliary hanger rod of the device. This rod is indicated by the numeral 20 and as stated is slidably fitted between the sleeve portions 12 and 15, in a manner clearly shown in Fig. 4 of the drawing. At one end 40 of the rod 21 there is provided a head 22 which is preferably circular in form and of a diameter slightly greater than the sleeve in which the rod 21 is slidably fitted. Before proceeding to a description of the 45 means provided for automatically extending the rod when the door of the display case is open, it may be stated, that the rod 21 may be slid outwardly to the position shown in Figs. 1 and 2 of the drawing and in order 50 that it may be held in this extended position, there is provided a leaf spring catch 23 which is secured as at 24 to the upper side of the sleeve in which the rod is fitted, and has its free portion bent to form a socket 25 and an 55 upwardly curved lip 26 located at the extremity of its said free portion. When the rod 21 is slid forwardly to bring the head 22 against the rear end of the sleeve, the periphery of the head will ride beneath the 60 free portion of the catch 23 and will engage in the socket 25, whereupon the rod will be held extended and in position to support such of the hangers 9 as have been removed from the rod. 7.

65 The means above mentioned and provided

for the purpose of automatically sliding the rod forwardly when the door B is swung to open position, consists of a suction cup 27 which is secured at the forward end of the rod 21 by means of a screw 28 the head of which is embedded in the neck of the cup, the concaved side of the cup being presented forwardly. By referring to Fig. 2 of the drawing it will be apparent that when the door is closed its inner face will strike 70 against the cup 27 whereupon the cup will adhere to the door and that when the door is swung to open position, a forward pull will be exerted upon the rod thereby sliding the same forwardly to about the position shown 75 in Figs. 1 and 2 of the drawing. The cup 27 will, of course, disengage from the door when the rod has been fully extended.

By referring to Fig. 3 of the drawing it will be noted that the forward end portion 80 of the rod 21 is threaded, as indicated at 29 and a circular head 30 is formed axially with an opening 31, the wall of which is threaded and this head is adjustably fitted onto the end of the rod 21 and serves as an 85 abutment to limit the sliding movement of the rod 21 by striking against the forward end of the sleeve in which this rod is slidably mounted. It will be apparent that by 90 adjusting this head 30, the forward end of the rod, or more specifically, the cup 27 may be caused to lie a greater or less distance in advance of the head 6 when the rod is slid inwardly to the fullest extent so that the cup may, by adjusting the head 30, be adjusted toward or from the inner face of the 95 door when the latter is in closed position, so as to insure of its proper engagement with the door. This head 30 also serves as a means to prevent the hangers 9 sliding off 100 from the rod 21 while the garments are being inspected. In order that the head will not mar any portion of the case which may come in contact therewith, for example when the device is applied to or employed in connection with a revolving hanger, the head 30 105 is formed peripherally with a groove 32 in which is seated a soft rubber ring 33.

In order that the salesman or saleslady may readily ascertain the size of the garments supported by the device, the convex 110 face of the plate 11 is formed with depressions 34 in each of which is disposed a disk 35 having printed or otherwise marked thereon the size of the garment and these 115 depressions are preferably located as illustrated in Fig. 1 of the drawing.

Having thus described the invention what is claimed as new is:—

1. In a device of the class described, the 125 combination with a slidable support including a relatively fixed hanger rod, of a bracket including a sleeve portion clamped to the said rod, means for holding the sleeve portion against turning upon the rod, and 130

an auxiliary hanger rod slidably mounted upon the bracket.

2. In a device of the class described, the combination with a slidable support including a relatively fixed hanger rod, of a bracket including a sleeve portion clamped to the said rod, means for holding the sleeve portion against turning upon the rod, and an auxiliary hanger rod slidably mounted upon the bracket, the auxiliary rod being offset with relation to the first mentioned hanger rod.

3. In a device of the class described, the combination with a support including a relatively fixed hanger rod, of a bracket fixed to the support upon the rod and including assembled sections, each consisting of a

curved plate having a sleeve portion at each of its ends, the sections being assembled with the sleeve portions matching, means 20 securing the sections in assembled relation with the sleeve sections at one end of each plate embracing the said hanger rod, the said plates extending upwardly and outwardly from the hanger rod, and an auxiliary hanger rod slidably mounted between the other sleeve sections.

In testimony whereof I affix my signature in presence of two witnesses.

JOHN A. SHEA. [L.S.]
